UNITED STATES PATENT OFFICE.

MEYNARDIE NELSON, OF LITTLETON, NORTH CAROLINA.

VERTICAL PAPER CUTTER.

Application filed April 14, 1922. Serial No. 552,520.

To all whom it may concern:

Be it known that I, MEYNARDIE NELSON, a citizen of the United States, and resident of Littleton, in the county of Halifax and 5 State of North Carolina, have invented certain new and useful Improvements in Vertical Paper Cutters, of which the following is a specification.

This invention relates to vertical paper- 10 cutters such as are adapted to be used in stores, for carrying rolls of wrapping paper and cutting the desired lengths of paper from the rolls.

My present invention has particular relation to types of paper cutters such as that shown in my previous Patent No. 1,116,834, issued November 10, 1914, and in my co-pending application Serial No. 625,572.

The object of my present improvements is 20 to provide a vertical paper-cutter of the type indicated, which will be especially adapted for carrying very heavy and large rolls of paper and which will be easily portable to the desired point of operation, which can be 25 operated with the same ease and facility as the smaller types of paper cutters which are used in a stationary position, and which can be furthermore "knocked-down" into a compact space and into but two parts or members for commercial transportation, which 30 parts or members can be conveniently and easily assembled co-operatively in setting up the paper cutter for use.

The cutter of the class to which my present 35 invention and improvements particularly relate is designed to carry paper rolls which in weight approximate 350 to 600 lbs. and are therefore difficult to handle under ordinary conditions and usually require 40 about 6 to 8 feet of floor space to afford the required area for operative use. The portable cutter embodying the features of my present invention and improvements is efficiently operative within the area of a small 45 floor space, approximately only 18 to 20 inches square, and the construction enables the handling of the largest and heaviest paper rolls, after the roll is positionally inserted in the cutter, with the same convenience 50 and facility and without greater expenditure and strength than is required in the usual handling of small or light rolls of paper in this general type of vertical paper-cutters. The latter usually rest upon a counter or other suitable support, whereas the 55 large paper cutters of the adaptable condi-

tions related to my present invention and carrying heavy rolls of paper must be supported upon the floor when in use, and the features of my present invention therefore 60 provide means for easily moving the cutter with its paper roll from desired place to place on the floor and for locking it in set position for use, substantially as hereinafter 65 set forth.

In the drawings—

Figure 1 is a perspective view of the cutter embodying my present improvements, partly broken away to show detail features 70 of construction.

Fig. 2 is a vertical sectional view, on an enlarged scale, through the lower portion of the device.

Fig. 3 is a vertical cross-section on the line 3—3, Fig. 2.

Fig. 4 is a horizontal cross-section on the line 4—4, Fig. 3.

Fig. 5 is a rear-end elevation of the lower portion of the cutter.

Corresponding parts in all the figures are 80 denoted by the same reference characters.

Referring to the drawings, 8 designates a main horizontal base, which is stationary when the cutter is in operative use and which supports the entire body structure and mechanism of the device. The body of this base is preferably constructed of hard wood with a metallic reinforcing sheet secured as a facing to both its top and bottom surfaces, as 85 at 9—10, and the edges of said wood body 90 may also be protected and reinforced by metal, as at 11. In the portable mounting of the main base 8, it is carried upon rollers, preferably three in number, said roller mountings having a fixed connection with 95 the base at certain points and comprising a guide roller having a revoluble-bearing connection with the base. In the preferred construction as herein illustrated, two of said 100 rollers are mounted respectively at the corners of the front edge portion of the base 8, as at 12—12, in fixed connection with the base, and the guide roller, 14, is mounted at the rear edge portion of the base and on the median longitudinal plane thereof, and is 105 carried by a standard, 15, having a revoluble bearing in the base and projectively extending upwardly therefrom. Mounted upon the upper portion of said standard is a fixed 110 cuff or bearing-block, 16, to which at its projective rear portion is pivoted a handle-bar, 17, of suitable length, with which the com-

plete device carrying the paper roll can be conveniently drawn about from place to place, and the guide action of the front roller 14 in the revoluble bearing of its carrying-standard 15 effected by lateral movement 5 of said handle.

After the cutter has been moved to the desired point it is desirable that it be locked in fixed position, and this is preferably effected by a brake acting upon the guide roller 14. In the preferred construction, a 10 brake, 18, is mounted to normally slide on the tread of the guide roller 14, and the revoluble standard 15 is tubular and internally 15 carries a coiled compression spring, 19, loosely mounted therein with its lower end resting on the brake, and within said tubular standard is slidably mounted a bolt, 20, having its lower end bearing against the spring 20 and its upper end projecting from the standard, and thus upon depression of said bolt the spring will be depressed and act upon the brake to cause locking of the guide roller 14 against revolution and consequently pre- 25 clude movement of the main base 8. The brake control is governed by movement of the handle bar, 17, and in the preferred construction the latter is bent at an angle, as at 21, which angle extends over the top of 30 the bolt 20 when the handle bar is swung upwardly and brought to position in line with the bolt, and in a further movement of the handle bears upon the top end of said bolt and causes depression thereof. The 35 handle bar itself is locked in its position in which it actuates the brake-control mechanism, when the cutter has been drawn or moved to the desired location, and for this purpose a keeper is provided to engage and 40 lock the handle at its upward limit of movement, the preferred construction comprising a collar, as at 22, secured to the main upright standard (hereinafter described) of the device, and having spring arms between which 45 the handle bar is gripped and from which it can readily be disengaged. Thus, in locked position of the handle bar, the guide wheel cannot move either in its roller action or laterally.

Upon the main front portion of the stationary base 8, is provided a race track, 23, carrying balls, 24, said track preferably having its ball channels spaced in circular series, which spaced condition, in lieu of a continuous race channel, is preferred in view of the relatively heavy weight of the paper roll which is carried upon the ball bearings in this type of cutter, and above said race track is mounted a spacer-ring, 25, having a circular series of openings corresponding to the spaced ball channels of the race track and operating to positionally control the balls therein.

The roll of paper, 26, is carried upon a 65 revolving base, 27, preferably constituted

by a metallic circular disc or plate which is in diameter adapted to the size of the paper roll used. Said revolving base operates above the main stationary base 8, and is mounted upon the balls 24, projecting 70 through and beyond the spacer-ring 25, so that said revolving base travels upon said balls and has a free action on ball bearings. The revolving base has an upwardly projecting stud, 28, axially located and forming 75 the bottom keeper for the roll of paper when the latter is in position upon said base, in which circumstances the projecting stud extends within the bore, 29, of the paper roll. The revolving base is secured in operative 80 connection with the main stationary base 8, and fixed in its revoluble position bearing upon the balls 24 which are retained between the race track 23 and spacer-ring 25 and the bottom of the revolving base, by a 85 rivet or bolt, 30, passing downwardly through the bore of the stud 28, through the spacer-ring 25, and through corresponding perforations in the fixed race track 23 and the main stationary base 8, said bolt being 90 headed to rest upon the stud 28 and having its bottom end permanently riveted at the under side of the stationary base.

The rolls of paper, for the handling of which my present improved cutter is designed, being of comparatively heavy or great weight, are liable to exert a strain upon the revolving base 27, or possibly affect the operative conditions thereof, in the act of placing such rolls in position upon the base when they are initially inserted for placement in position for carriage by the cutter device. I prefer therefore, under some conditions of use, to provide means whereby any liability of strain upon or 105 damage to the revolving base will be precluded in the circumstances just stated. For this purpose, a metallic segmental flange or rail, 31, is arranged to project upwardly 110 from the top of the main stationary base at one side thereof, extending to substantially the top plane of the revolving base and preferably corresponding to the plane of a portion of the periphery thereof. In placing or inserting the heavy paper roll to position in the cutter device, when the roll is 115 "trucked" up to the cutter for placement on the revolving base its bottom portion is initially set so that it will rest upon the metallic rail 31 and the center stud 28 of 120 said base and its weight will thus be sustained and supported upon said safety rail until the roll is slipped over upon the stud to vertical position and with the latter projecting within the lower end of the bore thereof. The heavy weight of the roll, until 125 it is fully positioned vertically with its bottom end resting upon the full surface of the revolving base, is thus not active upon the outer peripheral portion of the revolving

base beyond its central ball bearings, and does not exert a strain thereon, before its weight is brought directly over the ball-bearing and evenly distributed over the surface 5 of the revolving base.

The cutter, in its general operative mechanism, comprises a main upright standard, 32, in vertical alignment and secured in fixed position to the main stationary base 8 at 10 a point between the guide-roller standard 15 and the revolving base, said main standard 32 having an arm or extension, 33, projecting laterally at its top and carrying at its outer end a cylindrical socket, 34, the 15 bore of which is in alignment in a vertical plane with the axis of the revolving base 27, and the roll of paper is retained at its top by a pin, 35, insertibly mounted in said socket and projecting downwardly within 20 the top of the bore of the roll.

For "knock-down" purposes, the connection of the main standard 32 with the main stationary portable base 8 is preferably by means of a tubular stud, 36, projectively 25 carried at the top of said stationary base, and having the bore thereof extending entirely through the latter, the bottom end of the vertical standard 32 being inserted through said bore and the top edge of the 30 stud 36 being notched or recessed at diametrically-opposite sides, as at 37-37, to receive laterally-projecting pins or studs, 38-38, upon said standard and thus support the same within its socket-connection, 35 the standard being further positionally secured by a nut, 39, screwed home upon its projecting bottom end against the under side of the base 8.

The cutting mechanism is carried by the 40 main vertical standard 32, and comprises horizontal arms, 40, which are mounted in pivotal relation upon the standard, said arms being arranged in vertical series and collectively carrying at their outer ends the 45 knife or cutting blade, 41, which positionally bears longitudinally against the side of the paper roll and operates to cut the sheet which is taken therefrom. Said arms are 50 suitably retained and supported in their pivotal bearing upon the standard, and are preferably spring-controlled, as at 42, so that the spring tension is exerted to maintain the cutting edge of the blade against the surface of the paper roll.

55 The general arrangement of the standard, 32, and the cutting means comprising the spring-controlled arms carrying the cutting blade, may be varied as desired in the adaptation of the present improved cutter to 60 conditions of use, such parts being preferably substantially the same as are shown in my previous Patent No. 1,116,834, before mentioned, or as shown in my co-pending application Serial No. 625,572.

65 In view of the heavy character and size

of the rolls of paper to which my present invention and improvements are adapted, and the corresponding enlarged size and character and required strength of the portable device itself, excess strength is required 70 in the mounting of the longitudinal cutting blade and therefore a plurality of the cutter and sustaining arms 40 to the number of at least three or four is preferably provided, whereas in the small stationary vertical cutters adapted for lighter rolls of paper a plurality of but two of such supporting arms 75 meets the requirement for efficient operation.

Under the conditions of construction and relative arrangement of parts as comprised in the improved portable cutter constituting my present invention, the complete device can be "knocked-down" into but two parts 80 or members, for compactness in transportation, one part consisting of the main base 8 and the revolving base and other permanently connected elements which it carries and with the handle bar 17 folded down over the top of said base, and the other part 85 consisting of the main vertical standard 32 with the supporting arms and cutting blade and other elements which it carries, and said two parts or members can be readily and conveniently set up and secured in operative 90 relation in assembling the complete cutter 95 into condition for use.

The operation of the device, and the advantages of my present improvements, will 100 be readily understood from the foregoing description.

The improved features of construction provide not only the essential conditions of 105 strength and accurate and effective operation without the expenditure of increased power, in the convenient handling of very heavy rolls of paper, but also enable the moving of the device with ease and facility from place to place to position at the desired point of operation and for securely 110 locking the device against further movement when it has been brought to such position.

I do not desire to be understood as limiting myself to the detail construction and arrangement of parts as herein shown and described, as it is manifest that variations and modifications therein may be resorted to, in the adaptation of my invention to varying 115 conditions of use, without departing from the spirit and scope of my invention and improvements. I therefore reserve the right to all such variations and modifications as properly fall within the scope of my invention and the terms of the following claims.

Having thus described my invention, I claim and desire to secure by Letters Patent:

1. In a vertical paper-cutter of the class described, for mounting and revolvably carrying heavy rolls of paper in vertical posi- 120

tion for the operation of cutting, a portable mechanism comprising a main horizontal normally-stationary base member, a vertical standard projecting from said base member and adapted for carrying cutting elements operative upon the paper roll, roller means for portably sustaining said normally-stationary base member, said means comprising a guide roller having a revolute mounting in connection with the rear end portion of said base, brake means for locking said guide roller in fixed position, a handle member having a vertically-pivotal mounting at the rear of said stationary base at a point adjacent to and in rear of the position of said standard, said handle member being operative in its downward position as a tongue to draw said base upon its portable mounting, and means comprised in said handle member and operative to actuate said brake means to lock said guide roller when the handle member is in normal upright position towards said vertical standard.

25 2. In a vertical paper-cutter of the class described, for mounting and revolvably carrying heavy rolls of paper in vertical position for the operation of cutting, a portable mechanism comprising a main horizontal normally-stationary base member, a vertical standard projecting from said base member and adapted for carrying cutting elements operative upon the paper roll, roller means for portably sustaining said normally-stationary base member, said means comprising a guide roller having a revolute mounting in connection with the rear end portion of said base, brake means for locking said guide roller in fixed position, a handle member having a vertically-pivotal mounting at the rear of said stationary base at a point adjacent to and in rear of the position of said standard, said handle member being operative in its downward position as a tongue to draw said base upon its portable mounting, means comprised in said handle member and operative to actuate said brake means to lock said guide roller when the handle member is in normal upright position towards said vertical standard, and means for locking said handle member in its normal upright position with relation to said vertical standard and in its operative locking action upon the brake means.

30 3. In a vertical paper-cutter of the class described, for mounting and revolvably carrying heavy rolls of paper in vertical position for the operation of cutting, a portable mechanism comprising a main horizontal normally-stationary base member, a vertical standard projecting from said base member and adapted for carrying cutting elements operative upon the paper roll, roller means for portably sustaining said normally-stationary base member, said

means comprising a guide roller having a revoluble mounting in connection with the rear end portion of said base, brake means for locking said guide roller in fixed position, a handle member having a vertically-pivotal mounting at the rear of said stationary base at a point adjacent to and in rear of the position of said standard, 70 said handle member being operative in its downward position, as a tongue to draw said base upon its portable mounting, means comprised in said handle member and operative to actuate said brake means to lock said guide roller when the handle 75 is in normal upright position towards the vertical standard, and means carried by said vertical standard and engaging said handle member to lock the same in its normal upright position with relation to said vertical standard and in its operative locking 80 action upon the brake means. 85

4. In a vertical paper-cutter of the class described, for mounting and revolvably carrying heavy rolls of paper in vertical position for the operation of cutting, a portable mechanism comprising a main horizontal normally-stationary base member, a vertical standard projecting from said base member and adapted for carrying cutting elements operative upon the paper roll, 90 roller means for portably sustaining said normally-stationary base member, said means comprising a guide roller having a revolvable mounting in connection with the rear end portion of said base, a vertical 95 standard carrying said guide roller and having a revolvable mounting in connection with said stationary base at a point adjacent to and in rear of the position of said main fixed standard, brake means for locking said 100 guide roller in fixed position, a handle member pivotally mounted upon said revolvable standard to move vertically at right angles to the axis thereof and operative laterally to revolvably move said standard, said 105 handle member being operative in its downward movement as a tongue to draw the stationary base upon its portable mounting and comprising means operative to actuate said brake means to lock said guide roller 110 when the handle is in normal upright position towards the vertical standard, and means for locking said handle member in its normal upright position with relation to said vertical standard and in its operative 115 locking action upon the brake means.

5. In a vertical paper-cutter of the class described, for mounting and revolvably carrying heavy rolls of paper in vertical position for the operation of cutting, a portable mechanism comprising a main horizontal normally-stationary base member, a vertical standard projecting from said base member and adapted for carrying cutting elements operative upon the paper roll. 125 130

roller means for portably sustaining said normally-stationary base member, said means comprising a guide roller having a revolute mounting in connection with the 5 rear end portion of said base, a vertical standard carrying said guide roller and having a revolute mounting in connection with said stationary base at a point adjacent to and in rear of the position of said 10 main fixed standard, brake means for locking said guide roller in fixed position, means carried by said revolute standard and operative upon said brake means to actuate the same, and a handle member pivotally mounted upon said revolute standard to move vertically at right angles to the axis thereof and operative laterally to revolutely move said standard, said handle member being operative in its downward movement as a tongue to draw the stationary base upon its portable mounting and comprising means bearing upon said brake-controlling means of the revolute standard for actuating said brake means to lock said 15 guide roller when the handle member is in normal upright position towards said vertical fixed standard.

6. In a vertical paper-cutter of the class described, for mounting and revolutely carrying heavy rolls of paper in vertical position for the operation of cutting, a portable mechanism comprising a main horizontal normally-stationary base member, a vertical standard projecting from said base 20 member and adapted for carrying cutting elements operative upon the paper roll, roller means for portably sustaining said normally-stationary base member, said means comprising a guide roller having a revolute mounting in connection with the rear end portion of said base, a vertical standard carrying said guide roller and having a revolute mounting in connection with said stationary base at a point adjacent to and in rear of the position of said main fixed standard, brake means for locking said guide roller in fixed position, means carried by said revolute standard and operative upon said brake means to actuate the same, a handle member pivotally mounted upon said revolute standard to move vertically at right angles to the axis thereof and operative laterally to revolutely move said standard, said handle member being operative in its downward movement as a tongue to draw the stationary base upon its portable mounting and comprising means bearing upon said brake-controlling means of the revolute standard for actuating said brake means to lock said guide roller when the handle member is in normal upright position towards said vertical fixed standard, and means carried by said vertical fixed standard and engaging said handle member to lock the same in its normal upright position with relation to said vertical fixed standard.

In testimony whereof I have signed the foregoing specification.

MEYNARDIE NELSON.
